UNITED STATES PATENT OFFICE.

ALBERT H. BROWN, OF GRAND RAPIDS, MICHIGAN.

COAL-SCUTTLE.

1,227,527.

Specification of Letters Patent.

Patented May 22, 1917.

Application filed December 13, 1915. Serial No. 66,641.

To all whom it may concern:

Be it known that I, ALBERT H. BROWN, a citizen of the United States, residing at Grand Rapids, in the county of Kent and State of Michigan, have invented certain new and useful Improvements in Coal-Scuttles, of which the following is a specification.

My invention relates to improvements in coal scuttles, and its objects are: First, to provide a coal scuttle with which soft coal, slack, and very fine coal dust may be placed into a stove without the danger of the escape of dust, gas, &c. from the stove; second, to provide a coal scuttle with which fine coal dust may be placed into the stove at, or back of the center of the stove, and, third, to provide a coal scuttle with which soft, fine coal dust may be carried into, and through a room and placed into a stove without danger 20 of scattering the coal dust upon the carpet or floor.

I attain these objects by the construction and distribution of parts shown in the accompanying drawing, in which Figure 1 is 25 a sectional side view of my scuttle; Fig. 2 is a perspective of the scuttle; Fig. 3 shows the scuttle as it is used for placing coal or slack into a soft coal stove having the coal entrance in the side of the stove; Fig. 4 shows 30 the scuttle in position to carry.

Similar reference characters refer to similar parts throughout the several views.

This scuttle is made of sheet metal, as indicated, and is of rectangular oblong form 35 somewhat broader than it is thick, as indicated in Fig. 2. In other words, it is designed to be made so its form, in cross section, will exactly, or very closely fit the door opening *b*, in the front of the stove 7, so 40 that when properly inserted into the stove it will rest upon the slide 10 and will force the door 8, pivoted at 9, open for the free passage of the coal 11.

The scuttle is made up of the several parts 45 shown, comprising the rectangular oblong bucket 1, the bail 3 which is pivotally connected with the body 1, as at 5, in position a little above the longitudinal center of the body to insure carrying the body in vertical position, as in Fig. 4, and in position so that when folded backward, or downward, it will 50 reach back of, or below the handle 4 on the body 1 of the scuttle, as shown in Fig. 3, and indicated at *a* in Fig. 1. The door 2, pivoted

into the body 1 near the back somewhat below the top or open end of the body, as at 55 6, is designed to fit into the end of the body close enough so that no dust can escape around it when carrying very fine coal dust, and is so arranged that when the open end of 60 the scuttle is passed through the coal opening in the front of the stove, this door will be automatically opened by the pressure of the outflowing coal, as indicated in Fig. 3.

It will be readily understood that the position of discharging the coal into the stove, that is, in the center, back of the center or front of the center of the stove, depends upon the distance the open end of the scuttle 65 is passed into the stove.

When the coal has been emptied from the scuttle into the stove and the scuttle has been withdrawn the door 8 of the opening into the stove will close, as indicated by its dotted lines extending from the pivot point 9 to the 70 end of the slide 10, in Fig. 3.

It will be readily understood that with the scuttle made to closely fit into, but freely pass through the opening to the door 8, common in all stoves of this class, which door is 80 opened by the movements of the end of the scuttle, as indicated, and arranged to automatically close as the scuttle is being withdrawn from the opening *b*, it will be impossible for any dust or gas to escape from the 85 stove around the scuttle while coal is being poured into the stove or the scuttle is being withdrawn from the stove, even though the fuel being entered is of the very finest coal dust placed upon the market, or from the 90 softest coal mined, thus rendering the burning of this class of fuel just as cleanly and safe as the best quality of anthracite coal; a result that has been long sought for and, up to this time, has been deemed impossible to 95 accomplish, both by stove dealers and coal merchants, and by means of which the cost of fuel may be greatly reduced.

This scuttle may be used with equal success with hard coal, coke, and other like 100 fuels, and in pouring the fuel into the tops of the stoves the side walls of the scuttle prevent all possibility of dropping lumps of coal from the scuttle, over the edges of the stove and onto the floor. It is, also, very 105 much of an improvement over ordinary scuttles for feeding coal, coke, slack and other like fuels into furnaces, ranges and

like heating appliances, and may be made in any desired or necessary rectangular oblong form or size to meet the form or demands of the stove, furnace, &c., with which it is to be used.

What I claim as new, and desire to secure by Letters Patent of the United States, is:—

1. In a coal scuttle, a thin, broad, rectangular oblong body having a closed bottom and an open top, a bail pivotally connected with the sides of the body slightly above their centers, and a door pivotally connected with the sides of the body near the back thereof and somewhat below the top of the

body and arranged to incline upward and forward to the top of the front of the body.

2. In a coal scuttle, a rectangular oblong body having a closed bottom and an open top, a door pivotally connected with the sides of the body near the back a short distance below the top, a bail pivotally connected with the body near its longitudinal center, and a handle on one side of the body near the lower end.

Signed at Grand Rapids, Michigan, December 9, 1915.

ALBERT H. BROWN.
